TIME SWITCH FOR MOTORS

Jalmer M. Laiho, Skokie, Ill., assignor to Felt & Tarrant Manufacturing Company, Chicago, Ill., a corporation of Illinois

Application June 3, 1949, Serial No. 97,039

7 Claims. (Cl. 318—485)

1

This invention relates in general to electric circuit controlling mechanism, and more particularly to a novel time switch for automatically opening a motor circuit at the end of a predetermined interval.

A principal object of the invention is the provision, in a motor driven machine having manual control members selectively operable to initiate operation of the machine and cause the closing of a switch which results in energization of the motor, of means automatically effective to open the switch to de-energize the motor at the end of a predetermined time interval after operation of the last-to-be-operated of such manual control members.

Another object of the invention is to cause the motor of a calculating or business machine to be turned off automatically when the operator has finished using it, so that carelessness on the part of the operator cannot result in the machine motor continuing to run indefinitely.

More specifically, the present invention comprises the addition to a motor driven calculating machine, having the usual digit keys and cancelling crank as manual control members, of time switch mechanism operable to start the motor in response to actuation of any digit key or the cancelling crank and to stop the motor automatically at the end of a predetermined time interval beginning with such starting of the motor.

Another object is the provision of such time switch mechanism which will be reset automatically by each subsequent operation of a control member which is effected before the expiration of such time interval, starting from the time of manual release of the last control member to have been operated, so as to avoid unnecessary starting and stopping of the motor during the performance of any normal series of related calculations.

Numerous other objects and advantages of the invention will be apparent as it is better understood from the following description, which, when taken in connection with the accompanying drawings, discloses a preferred embodiment thereof.

In the drawings:

Figure 1 is a fragmentary elevational view of a calculating machine embodying the instant invention, as seen from the right side of the machine, showing the usual cancelling crank and the normal position assumed by the time switch mechanism following de-energization of the motor;

2

Fig. 2 is a detail rear elevation of the time switch mechanism, as seen from the right end of Fig. 1;

Fig. 3 is a fragmentary elevation similar to Fig. 1, showing the positions assumed by the various parts of the time switch mechanism upon actuation of a manual control member;

Fig. 4 is a detail view similar to Fig. 3 of the switch-opening rack and immediately associated parts, showing the positions assumed thereby just prior to automatic opening of the switch;

Fig. 5 is a longitudinal elevation of the machine, with parts omitted, as seen from the left side thereof, showing the power drive connections from the motor to the time switch mechanism and the means for actuating the latter in response to digit key operation; and

Fig. 6 is a diagrammatic view of the motor circuit.

Referring more particularly to Fig. 5 of the drawings, reference numeral 21 designates in general a calculating machine of the type disclosed in United States Letters Patent No. 2,063,962, issued December 15, 1936, and my prior U. S. Patent No. 2,410,823, issued November 12, 1946, this figure corresponding generally with Fig. 2 of each of said prior patents. This calculating machine is provided with a plurality of denominational orders of accumulator and actuating mechanisms, the latter being mounted on skeleton frame members or partition plates 22 held together in spaced relationship by transverse tie rods 23, and registration control means including a column of digital control keys 24 for each such order which are selectively manually depressible to determine the digital degree of actuation to be imparted by their associated actuating mechanism to the accumulator. Such mechanism is fully described in said prior patents, so that a more particular description herein is not necessary, reference being had to those patents for a complete explanation of the specific arrangement of the parts and operation of this type of calculating machine, including an electric motor 44 drivingly connected by suitable gearing (Fig. 5) with a power drive shaft 45 extending transversely of the machine across the several denominational orders and comprising an element of the cyclically operable registering means of the machine.

It is sufficient for a complete understanding of the present invention to know that in this type of calculating machine, which comprises only one of many possible devices with which the instant invention may be employed, depression

of any digit key 24 causes its stem 47 to engage and move downwardly a longitudinally extending bar 48 (Fig. 5) forming part of a parallel motion device, one such device being located in each denominational order of the machine. Each bar 48 is pivoted at the front at 49 and at the rear at 51 to levers 52 and 53, respectively, which in turn are pivoted upon cross shafts or rods 54 extending through the partition plates 22. Completing each parallel motion device is a link 55 which is pivotally connected at 56 to the front lever 52 and at 57 to the rear lever 53. It will thus be seen that depression of any digit key 24 will cause forward movement (to the right in Fig. 5) of the lower link 55 of the associated parallel motion device, and it is this resulting forward movement of the stud 56, comprising the pivotal connection between the link 55 and the lever 52, that is employed in connection with the present invention, in a manner to be fully described hereinafter. For convenience, all of the reference numerals so far used herein are the same as those applied to the same parts in my said prior Patent No. 2,410,823.

As is customary in this type of calculating machine, other registration control means also are provided comprising means for zeroizing or cancelling any registration from the accumulator. In the prior patents previously referred to, such zeroizing of the accumulator is accomplished by rocking the supporting frame of the accumulator to disengage the latter from its actuating gears, and the specific mechanism for accomplishing this cancelling function is fully disclosed in U. S. Letters Patent No. 1,357,748, issued November 2, 1920. The zeroizing mechanism of the instant machine is substantially identical to that described in this latter patent, so that only so much thereof is illustrated in Fig. 1 herein as is necessary to a complete understanding of its structural and functional relationship with the present invention. A short transverse shaft 70 (Fig. 1) is journaled in a suitable bearing in the right hand side plate 22, and the lower end of a zeroizing control handle or cancelling crank 71 is secured to the outer end of this shaft. A segment 72 is fixed upon the inner end of this short shaft 70, and a link 73 pivotally interconnects the segment 72 and a depending lever 74 that is pivoted at 75 on the machine frame. These parts are numbered the same as their counterparts in Patent No. 1,357,748, and as explained in detail in said patent, forward movement of the upper end of cancelling crank 71 (counter-clockwise movement thereof viewing Fig. 1) will move the link 73 forwardly to swing the depending lever 74 in a counter-clockwise direction to actuate a suitable rock shaft which effects the gear detraining and accumulator zeroizing previously mentioned.

Pivots secured at its forward end to this depending lever 74 and the link 73 is a rearwardly extending link 121, the rear end of which is pivotally connected to the upper end of a lever 153. This lever 153 is fixed intermediate its ends on the right hand end of a cross shaft 152 having suitable bearings in the skeleton frame members 22 and extending transversely through all denominational orders of the machine. The lever 153 is urged in a clockwise direction (viewing Fig. 1) by a spring 155 secured thereto at one end, adjacent the lower end thereof, and at its other or forward end to a cross shaft 156 mounted in and extending through the frame plates 22. These several parts are numbered

herein the same as their counterparts which are fully disclosed in U. S. Letters Patent No. 2,021,393, issued November 19, 1935. Counter-clockwise movement of the cancelling crank 71 from its normal position of Fig. 1 to effect zeroizing of the accumulator, in the manner noted above, thus will carry the link 121 forwardly to impart counter-clockwise movement to lever 153 from its position of Fig. 1 to its position of Fig. 3, and also considerably beyond the position of Fig. 3. The resulting rotation of shaft 152, as specifically explained in said prior Patent No. 2,021,393, releases error control or key locking mechanisms which may have been set by mis-manipulation of one or more digit keys 24. It is the rearward movement of the lower end of this lever 153 thus resulting from operation of the cancelling crank 71 that is employed in connection with the present invention.

To adapt this otherwise old lever 153 for use with the novel mechanism comprising the instant invention, its lower end has been lengthened and provided with an outwardly extending tooth 201. This tooth 201 cooperates with a notch 202 (Fig. 25) in the forward end of the lower arm of a two-armed pawl 203 pivotally mounted at 204 on a link 205. A "grasshopper" type of spring 206 mounted on the pivot 204 engages the underside of the link 205 at one end and the forward edge of an upper arm 207 of the pawl 203 at its other end. The lower arm of the pawl 203 has a lateral extension or shelf 208 normally engaging the lower edge of the link 205 to limit clockwise movement of the pawl 203 by the spring 206. A stud 209 is mounted on the adjacent skeleton frame member 22 for cooperation with the upper arm 207 of the pawl 203 in a manner to be later described.

The forward end of the link 205 is provided with a slot 211 slidably engaging the shaft 156. A spring 212 is connected at its forward end to the cross shaft 156 and at its rear end at 213 to the link 205 to normally maintain the latter in its position of Fig. 1 with the rear end of the slot 211 in abutting engagement with the shaft 156. Adjacent its rear end, the link 205 is pivotally connected at 214 with the upper end of a lever 215 in turn pivotally mounted at its lower end on a cross shaft 216 mounted in the frame plates 22. The rear end of the link 205 is pivotally connected in any suitable manner at 217 with the forward end of a link 218 in turn pivotally connected at its rear end with an upwardly extending arm of a bell crank lever 219. This lever 219 is pivotally mounted on a cross shaft 221 on which shaft the forward end of a latch pawl or holding detent 222 is also pivotally mounted. This holding pawl 222 is provided with a laterally extending stud 223 which is held in engagement with the under surface of the lower, rearwardly extending arm of the lever 219 by a "grasshopper" type spring 224, the latter being mounted on the cross shaft 221 and engaging the under surface of the stud 223 at one end and the forward edge of the upper arm of the bell crank 219 at its other end.

A stud 225 extends laterally of the machine, but not inwardly sufficient to contact the lever 219, for movement-limiting engagement with the forward end of a switch-opening ratchet member or slide bar 226. As best seen in Fig. 2, an auxiliary frame is provided for supporting those parts of the instant time switch mechanism mounted at the rear of the machine, which comprises a pair of vertical side plates 227 secured

together in parallel spaced relationship by suitable bolts and spacer sleeves, as indicated at 228, this sub-frame assembly being mounted in any desired manner on the inner side of the right hand frame plate 22, and the outer plate 227 carries the laterally extending stud 225. The outer plate 227 of this time switch sub-frame also is provided with a pair of inwardly extending shouldered studs 229 which are slidably engaged, respectively, by a pair of horizontally disposed slots 231 formed in the ratchet slide bar 226. This ratchet slide bar 226 thus is mounted for horizontal sliding movement, and it is provided on its lower edge with a plurality of ratchet teeth 232 adjacent its forward end for cooperation with the holding pawl 222. The pawl 222 normally engages the forward one of these ratchet teeth 232 to maintain the ratchet slide bar 226 in its rearmost position of Fig. 1, wherein an insulated roller 233 mounted on the rear end of the slide bar 226 and extending laterally therefrom engages against the lower end of a spring contact member 234 to maintain the contact thereof out of engagement with the contact of a second depending contact member 235. These contact members 234, 235 comprise a switch connected in series with the motor 44. As shown in Fig. 6, the contact member 234 is connected to one side 236 of a suitable source of electrical energy, the other side 237 of such supply being connected to one side of the motor 44, and the other side of the latter being connected by a lead 238 to the other contact member 235. It will be understood that any desired circuit arrangement other than that illustrated in Fig. 6 may be employed, so long as the closing and opening of the switch comprising the contact members 234, 235 results in the energization and de-energization, respectively, of the motor 44.

Referring again to Figs. 1 and 2, the upper ends of the contact members 234, 235 are rigidly mounted in a block 239 of insulating material which is secured intermediate its ends by rivets 241, or the like, to a bracket 242 comprising an upwardly and rearwardly extending end portion of the outer side plate 227, the inner plate 227 terminating at its upper rear end adjacent the forward edge of the insulating block 239. Such mounting of the contact members 234, 235 on this insulating block 239 preferably is accomplished by providing the contact members with lateral extensions at their upper ends (Fig. 1) in the form of ears 243 extending therefrom rearwardly and forwardly, respectively. Each of these ears 243 is connected to the insulating block 239 by a pair of rivets 244, the upper one of which preferably is hollow and formed at its inner end as a socket to receive the ends of the leads 236 and 238, respectively (Figs. 2 and 6).

A transverse shaft 245 extends between the sub-frame plates 227 adjacent their upper edges, being suitably secured thereto in any desired manner, upon which the upper end of a depending lever 246 is pivotally mounted. As best seen in Fig. 2, this upper end of the lever 246 is reversely bent to provide a saddle-like hub portion having laterally spaced lugs through which the shaft 245 extends to insure lateral stability of the lever. A spring 247 is connected at its rear end to this lever 246 below the shaft 245 and at its forward end to a shaft 248 extending transversely through the machine. The lower end of the depending lever 246 is maintained by this spring 247 in engagement with a stud pin 249 extending laterally from the ratchet slide bar 226.

226. Also mounted pivotally on the shaft 245 is a bell crank lever 251 which, as seen in Fig. 2, is provided with a laterally extending, reversely bent hub portion engaging the shaft in the same manner as the hub portion of the lever 246. These hub portions of the levers 246 and 251 are so dimensioned as to be pivotably confined adjacent each other between the inner surfaces of the side plates 227 to prevent lateral movement of the levers. The upper arm of the bell crank lever 251 extends forwardly and is connected at its forward end to the upper end of a spring 252, the lower end of which in turn is connected to a suitable stud extending inwardly from the outer sub-frame plate 227. The lower end of the depending arm of this bell crank lever 251 terminates adjacent a shouldered stud 253 extending between, and suitably mounted in, the sub-frame plates 227 (Fig. 2). Above this stud 253, the lower end portion of the lever 251 has a stud shaft 254 mounted therein which extends outwardly from the lever and pivotally supports a pawl 255 at its outer end which is disposed in vertical alignment with the ratchet slide bar 226 which it is adapted to move rearwardly of the machine. Mounted on this stud shaft 254 is a "grasshopper" type spring 256, one end of which engages the forward edge of the lever 251 and the other end of which engages the lower edge 30 of the pawl 255 to urge the latter in a counter-clockwise direction (Fig. 1) on the shaft 254 to engage the rear end thereof with actuating teeth 257 provided on the under edge of the ratchet slide bar 226. This slide-actuating pawl 255 is provided with a depending tail piece which operates with the transverse stud 253, in a manner to be later described in detail.

Intermediate its ends, the depending arm of the bell crank lever 251 is provided with a laterally extending lug 258 (Figs. 1 and 2) having a rear surface parallel with the adjacent rear edge of the lever 251 and extending therefrom inwardly of the machine, and an upper edge (Fig. 4) sloping downwardly toward the main portion 45 of the lever 251. This rear surface and upper edge of the lug 258 function as cam surfaces and cooperate, respectively, with a first cam roller 259 and a second cam roller 260 of each of two pairs of such rollers mounted on the outer side 50 of a gear 261. As best seen in Fig. 1, this gear 261 is rotatably mounted upon a horizontal shaft 262 extending between, and supported by, the sub-frame plates 227. The said first cam rollers 259 of each of the two pairs of rollers 259, 260 are disposed diametrically opposite each other, as are the second cam rollers 260 of each such pair of rollers, and each roller 259 is mounted at a greater radial distance from the shaft 262 than its associated second roller 260. The gear 261 is actuated by a pinion 263 meshing therewith (Fig. 1), which is rotatably supported on a suitable shaft 263' secured to the sub-frame plates 227. A gear 264 is similarly mounted on this shaft 263' and is rigidly connected to the pinion 263. This gear 264 in turn meshes with a pinion 265 secured to the power drive shaft 45. Since the motor 44, through the gear train illustrated in Fig. 5, drives the power drive shaft 45 in a clockwise direction (viewing Fig. 1), the gear 261 likewise is rotated in a clockwise direction, through the agency of the pinion 265, gear 264 and pinion 263. Any desired gear ratio may be employed between the power drive shaft 45 and the gear 261, and the cam rollers 259, 260 are so mounted on this gear 261 that they will assume

substantially their positions of Fig. 1 after the motor 44 has been de-energized and the several parts driven thereby have come to rest. As shown in Fig. 1, pawl 255 then will be disengaged from ratchet slide bar 226.

The means for releasing the ratchet slide bar 226 in response to actuation of the cancelling crank 71 comprises the lever 153; which is swung from its normal position of Fig. 1 to that of Fig. 3 by virtue of the members 70, 72, 73, 74 and 127 interconnecting it with the cancelling crank 71; the tooth 201 on this lever 153, the pawl 203, links 205 and 218, and the lever 219, which, when thus moved to their positions of Fig. 3, release the holding pawl 222 from the ratchet slide bar 226. Since the pawl 255 normally is in its disengaged position of Fig. 1 at this time, spring 241 thus will be permitted to swing lever 246 clockwise from its position of Fig. 1 to slide the ratchet bar 226 to its position of Fig. 3, through the agency of stud pin 249. Such forward movement of the ratchet slide bar 226 is limited by contact with the stud 225. Additional time switch control means are provided, which will now be described, comprising mechanism for similarly releasing the ratchet slide bar 226 in response to actuation of any of the digit keys 24 of the machine.

Referring to Fig. 5, an upstanding finger 266 is provided in each denominational order of the machine for cooperation at its upper end with the associated stud 56 which comprises the front pivot between the link 55 and the lever 52 of the key-actuated parallel motion device of that order. The lower ends of each of these fingers 266 are crimped, or otherwise suitably rigidly secured, to a rock shaft 267 extending transversely across the machine. In the present embodiment of the invention, this shaft 267 is illustrated as being rectangular in cross section, and it is rotatably mounted at 268 in any suitable manner at each end in a supporting plate 269. These end plates 269 are supported by the cross shaft 156 and an adjacent transverse tie rod 23. Consequently, depression of any one of the digit keys 24 will cause the finger 266 in that denominational order to be swung forwardly at its upper end from its full line to its broken line position of Fig. 5.

Referring now to Figs. 1 and 3, the rock shaft 267 is provided adjacent its right hand end with an upstanding lever 271 secured thereto at its lower end in similar manner to the fingers 266. The upper end of this lever 271 is pivotally connected to the forward end of a link 272, the rear end of which is pivotally connected to the upper arm of a bell crank lever 273. The bell crank lever 273 is pivotally mounted on a shaft 274 extending transversely through the machine, and is provided at its lower end with a laterally extending stud pin 275. This pin 275 normally engages the forward surface of a shoulder 276 formed on the upper edge of the link 205 adjacent the forward end thereof. When the fingers 266 are in their normal full line positions of Fig. 5, the lever 271, link 272 and bell crank 273 are disposed in their full line positions of Figs. 1 and 3. Forward rocking of any of the fingers 266 in response to depression of a digit key 24, as previously described, thus will move these parts 271-273 to their broken line positions of Fig. 3, which results in rearward movement of the link 205 by the pin 275 to its position of Fig. 3, which is the same actuation of this link 205 as that effected in response to forward movement of the cancelling crank 71. This is true because

such forward movement of cancelling crank 71 results in swinging of the lever 153 from its position of Fig. 1 to that of Fig 3, whereby its tooth 201 cooperating with the notch 202 will move the pawl 203 and the link 205 rearwardly. During the final increment of such movement of the link 205 in response to forward swinging of the cancelling crank 71, the upper arm 207 of the pawl 203 will strike the stud 209 to impart counter-clockwise movement to the pawl relative to the link 205 to disengage the notch 202 from the tooth 201. These parts are shown in Fig. 3 in the positions assumed just prior to such disengagement, and complete forward swinging of the cancelling crank 71 will impart additional counter-clockwise movement to the lever 153 from its position of Fig. 3. Consequently, even though the cancelling crank 71 be held in its forward actuated position, the link 205 and connected parts will be returned from their rear-most positions of Fig. 3 by the spring 212 to their normal positions of Fig. 1, with the top edge of the main arm of the pawl 203 underlying the tooth 201. As differentiating from such actuation of the link 205 in response to manual operation of the cancelling crank 71, this link 205 and its connected parts will not be returned to their normal positions of Fig. 1 by the spring 212 following their actuation in response to depression of a digit key 24 until the latter is released.

Such rearward movement of the link 205, in response either to actuation of a digit key 24 or the cancelling crank 71, will release the latch pawl or holding detent 222 from the teeth 232 of the ratchet slide bar 226 in response to the resulting movement of the bell crank lever 219 from its position of Fig. 1 to that shown in Fig. 3. Since the pawl 255 normally is held out of engagement with the teeth 237 of slide bar 226 because spring 252 maintains this pawl and the bell crank lever 251 in its position of Fig. 1, such release of the holding pawl 222 from the teeth 232 results in forward sliding of the ratchet bar 226 on the studs 229 under the influence of spring 247, which urges the lower end of the lever 246 forwardly, until the forward end of the ratchet slide bar 226 strikes stop pin 225. These several parts thus assume their position of Fig. 3 upon actuation of a machine control key, and the forward movement of the ratchet slide bar 226 permits closing of the switch, comprising contact members 234 and 235, to energize the motor 44. It will be readily understood, of course, that the holding pawl 222 will be returned to engaging relationship with the rearmost of the teeth 232 immediately thereafter, either as the cancelling crank 71 passes approximately the middle of its forward swinging movement, or upon manual release of the digit key 24, the depression of which instituted disengagement of the pawl 222.

As previously explained, all of the several parts of the instant time switch mechanism normally are disposed in their positions of Fig. 1. In response to the above-described energization of the motor 44, the large gear 261 is rotated in a clockwise direction from this normal position. The first cam roller 259 of the leading uppermost pair of rollers 259, 260 illustrated in this figure thereupon moves the lug 258 forwardly to swing the bell crank lever 251 clockwise about the shaft 245 and against the action of spring 252 to a position to the left of that shown in Fig. 4. This forward movement of the lower end of the lever 251 carries the stud shaft 254 forwardly

and permits the spring 256 to lift the nose of pawl 255 into engagement with the lower edge of ratchet slide bar 226. Continued rotation of gear 261 carries the leading cam roller 259 beyond the lug 258 and moves the second cam roller 260 of this pair to its position of Fig. 4. Immediately upon disengagement of the first cam roller 259 from the lug 258, the spring 252 functions to return the bell crank lever 251 in a counter-clockwise direction about the shaft 245 to its position of Fig. 4, wherein the nose of pawl 255 engages the rearmost tooth 257 of ratchet slide bar 226. The second cam roller 260 is provided to assist the spring 252 and positively insure complete return movement of this lever 251 to its position of Fig. 1. During such final increment of return movement of the lever 251, thus positively effected by cam action of roller 260 against the upper cam edge of lug 258 from the position illustrated in Fig. 4, pawl 255 is moved rearwardly to slide the ratchet bar 226 rearwardly the distance of one tooth 257, whereupon continued movement of these parts results in disengagement of the pawl 255 from rack bar 226 by virtue of engagement of its tail piece against rod 253. In the meantime, the holding pawl 222 has been moved out of engagement with the rearmost or first tooth 232 and into engagement with the second such tooth to maintain the slide bar 226 in such intermediate position (as shown in Fig. 4).

As illustrated herein, three such latch teeth 232 and two actuating teeth 257 are provided on the slide bar 226. Consequently, repetition of such incremental movement rearwardly of the bar 226 effected by the second pair of cam rollers 259, 260 as they in turn actively engage cam lug 258 in the continued rotation of gear 261, will move rack bar 226 from its position of Fig. 4 back to its normal position of Fig. 1. During the last portion of such incremental rearward movement of the slide bar 226, the insulated roll 233 will move switch member 234 rearwardly out of contact with switch member 235 to break the circuit and cause de-energization of motor 44. The overrunning of the motor and members driven thereby after such de-energization, due to the momentum of the parts, will insure return of the several members to their position of Fig. 1. It will be readily understood that the particular gear ratio herein illustrated as obtaining between 50 pinion 265 and gear 261, and the specific number of latching and actuating teeth 232 and 257 shown, may be varied to obtain any desired predetermined time interval between closing of the motor switch in response to manual operation of a machine control member and automatic re-opening of such switch. In other words, depending upon the particular construction, normal mode of operation and operating cycle time of the specific machine in which the instant invention is to be incorporated, the person employing this invention may so design the several parts, as hereinbefore described, as to obtain the most satisfactory predetermined delayed shut-off of the motor. The specific embodiment of the invention herein illustrated and described greatly facilitates its incorporation in the type of calculating machine disclosed in the referenced prior patents, since it makes use of the mechanism old therein and is particularly adapted for such incorporation by virtue of the assembly of the major portion of the novel mechanism in the sub-frame 227, 228. It will be understood, however, that it is not intended to limit the scope of this invention to the specific embodiment herein dis-

closed, nor to its use only with that type of machine illustrated in such patents.

It is thought that the invention and its attendant advantages will be understood from the foregoing description, and it will be apparent that various changes may be made in the form, construction and arrangement of the parts without departing from the spirit and scope of the invention or sacrificing all of its material advantages, the form hereinbefore described and illustrated in the drawings being merely a preferred embodiment.

I claim:

1. In a time switch for a motor operated machine having a plurality of manually operable members for selectively controlling machine operation and a motor controlling switch normally maintained open by a switch-opening member, spring means for retracting said switch-opening member from normal position, a latch pawl normally engaging said switch-opening member to prevent retraction thereof by said spring means, a link pivotally connected to said pawl and spring-urged to normally maintain the pawl 20 in latching engagement with said switch-opening member, and connections actuated by said manually operable members to move said link in response to actuation of one of said manually operable members to disengage said pawl from said switch-opening member and automatically releasable from said link to effect re-engagement of said pawl with said switch-opening member, whereby each successive operation of any one of said manually operable members will disengage 30 said pawl from said switch-opening member.

2. A time switch according to claim 1, wherein said connections include a toothed lever rockable by a said manually operable member, a bell crank lever pivotally mounted on said link and having a first arm spring-urged into engagement with said toothed lever and a second arm 40 standing from said link, and a stationary stop against which said second arm is moved to disengage said first arm from said toothed lever 45 at the end of the latching pawl disengaging movement imparted thereby to said link to enable immediate return of said link to normal position.

3. In a time switch for a motor operated machine having a plurality of manually operable members for selectively controlling operation and a motor controlling switch normally maintained open by a switch-opening member, spring means for retracting said switch-opening member from normal position, a latch pawl normally engaging said switch-opening member to prevent retraction thereof by said spring means, a link pivotally connected to said pawl and spring-urged to normally maintain the same in latching engagement with said switch-opening member, a rock shaft having a plurality of upstanding fingers operatively associated respectively with said manually operable members, and connections interposed between said rock shaft and said link for actuating the latter to disengage said pawl from said switch-closing member upon actuation of any one of said manually operable members.

4. In a time switch mechanism for a motor operated machine having a motor controlling switch normally maintained open by a slide mechanism manually releasable to effect closing of the switch, means for cyclically advancing said slide mechanism in step-by-step movements to re-open said motor controlling switch, comprising a gear train driven by the machine motor

11

and including a driven gear, a lever, an advancing pawl pivotally mounted on said lever and spring urged toward engagement with said slide mechanism, stationary stop means, spring means for moving said lever to impart advancing movement to said pawl and subsequently to move said pawl into engagement with said stop means to effect disengagement thereof from said slide mechanism, and cooperating cam means carried by said driven gear and said lever for imparting retractive movement to said lever to tension said spring means.

5. Time switch mechanism according to claim 4, wherein said cam means includes a member carried by said driven gear operable after tensioning and release of said spring means to positively insure complete pawl advancing movement of said lever.

6. Time switch mechanism for motor operated calculating machines which have an electric circuit through the motor, a switch for controlling said circuit, and a plurality of control members selectively operable manually to control operation of the machine; comprising a ratchet member normally engaging said switch to maintain the same in open position, means constraining said ratchet member for movement out of engagement with said switch, detent means normally engaging said ratchet member to prevent

movement thereof by said constraining means, link mechanism operable in response to manual actuation of a said control member to disengage said detent means from said ratchet member to enable closing of said switch by said constraining means, spring means operable to return said link mechanism following such actuation of said control member to re-engage said detent means with said ratchet member, a ratchet member driving pawl, a second spring means normally maintaining said pawl out of engagement with said ratchet member, and means cyclically operable by said motor to successively tension said second spring means and release the same to actuate said driving pawl to move said ratchet member toward switch opening position against the action of said constraining means.

7. Time switch mechanism according to claim 6, wherein said cyclically operable means comprises a cam member operable after tension and release of said second spring means to positively effect complete actuation of said driving pawl.
